UNITED STATES PATENT OFFICE.

WILLIAM KNOBLOCK, OF LONG ISLAND CITY, NEW YORK.

CONTAINER.

Application filed May 29, 1924. Serial No. 716,800.

To all whom it may concern:

Be it known that I, WILLIAM KNOBLOCK, a citizen of the United States, residing at Long Island City, in the county of Queens, 5 State of New York, have invented certain new and useful Improvements in Containers, of which the following is a specification.

The object of this invention is to provide an improved box or container particularly 10 adapted to receive and hold the usual one or more cells comprising an electric storage battery, such as those used in lighting and ignition systems in automobiles.

A further object is to provide an article 15 of the class described which can be formed, pressed or moulded from electric insulating material, such as will also be proof against attack by the acids used in secondary or storage batteries, and to provide a marginal 20 member removably secured to the said box or container, said member being adapted to retain battery cells therein even should the container and contents be upset into an inverted position, while said member also 25 when in operative position is adapted to secure in fixed position with respect to said container any desired number of handles for supporting and carrying the article and its contents from place to place.

With these and other objects in mind, this 30 invention comprises further details of construction and operation fully and clearly brought out in the following description, when read in conjunction with the accompanying drawings, in which Fig. 1 is a vertical longitudinal section through the improved container in combination with a set 35 of storage battery cells in operative position therein; Fig. 2 is a fragmentary detail view showing the union of one of the handles, the adjacent portion of the container and the marginal member for securing the two together; Fig. 3 is a vertical transverse section of the upper portion of the container 40 per se; Fig. 4 is a perspective view of the marginal securing member; Fig. 5 is a perspective view of the container; Fig. 6 is a perspective view of one of the handles.

Referring to the drawings, a box or container 45 of suitable material, such as wood, hard rubber, or the like, is provided, the same comprising a bottom 1, bounded by upwardly extending side walls 2 and end walls 3, said walls adjacent to their uppermost portions being reduced transversely at 4 to approximately one-half of their cross-

section, and forming at the lower extent of said reduced portion a horizontal shelf or ledge 5, from which ledge there extend upwardly at spaced intervals semi-cylindrical 60 grooves 6, in the reduced portion 4, and opening directly in the uppermost face of said reduced portion. This said portion is furthermore provided at spaced intervals with transversely extending apertures 7, 65 countersunk at 8, and adapted to receive conical bushings 9.

A marginal member, such as is shown in perspective in Fig. 4, is provided, the same comprising upwardly extending sides 10 and 70 ends 11, adapted to be slid downwardly into the upper portion of the container, and when in normal operative position the combined thickness of the walls 10 and 11, together with the respective reduced portions 75 4 of the walls 2 and 3, is equal to the thickness of the lower portion of the said walls of the container. The upper or marginal member is provided upon its outer upright surfaces with spaced slots 12, which register with the slots 6, and at their upper ends extend through an outwardly projecting peripheral flange 13 lying in substantially the same plane with an inwardly projecting flange 14, while the lower ends of said slots 80 85 communicate with recesses 15 in the lower edge portions of said marginal member.

A handle or other suitable lifting device 90 such as is shown in Fig. 6 is provided, the same comprising a horizontal portion 16 terminating oppositely in downwardly extending portions 17, which latter terminate at their lower extremities in laterally extending projections 18. This lifting device is adapted to be placed within two of the adjacent grooves 12 of the upper marginal member, and so arranged that the projections 18 lie within the recesses 15 of said member, after which said marginal member is slid downwardly into operative position 95 100 with respect to the container, and so that the outer semi-cylindrical portion of the sides 17 of the shifting device lie within the slots 6.

When the various elements have thus been 105 assembled, screws 19 are passed through the bushings 8 and apertures 7 of the reduced portion 4 of the container, and thence into threaded engagement with a preferably metal bushing 20, which may be moulded or otherwise fixed within an aperture 21 in the 110 sides of the marginal member, this construc-

tion insuring a firm cooperation between said marginal member and the adjacent reduced portions of the walls of the container, and preventing the lifting device from either longitudinal or transverse movement with respect to said united members.

Although this container is adapted to many uses, it has in this instance been particularly designed to hold the usual cells 22 of a storage battery, in which instance the inwardly directed flange 14 of the marginal member cooperates with the upper peripheral portion of the upper surface of the cover 23 of said battery cells, and holds said cover in firm co-operative relation with the side walls 24 of said cells indirectly through the medium of a peripherally yielding gasket 25.

Thus, if the container and contents, similar to the arrangement shown in Fig. 1, are over-turned into a completely inverted position, it is obvious that the respective cells cannot be dislodged from within said container, nor will the acids of said cells be permitted to escape therefrom past the said peripheral gaskets. And, furthermore, the handles make it possible to readily transport said container and contents from place to place in any convenient manner.

Having thus described my invention, what I claim and desire to protect by Letters Patent of the United States is:—

1. A container, comprising a hollow member having side walls, the upper portions of said walls being reduced in cross-section upon one side, and a member adapted to be inserted within and in slidable co-operation with said reduced portions, and an inwardly directed flange carried by said second member to retain the contents within said first member.

2. A container, comprising a hollow member having side walls, the upper portions of said walls being reduced in cross-section upon one side, a member adapted to be inserted within and in slidable co-operation with said reduced portions, said member having an outer flange overhanging the interior of said first member, and means extending through said reduced portions and into said second member to secure said members together.

3. A container, comprising a hollow member having a groove in its inner wall surface, a member adapted to be inserted and fixed within said first member and having a groove registering with said first

groove, a lifting device adapted to be positioned in said grooves, and means to secure said members together to prevent the accidental withdrawal of said lifting device.

4. A container, comprising a hollow member having a groove in its inner wall surface, a member adapted to be inserted and fixed within said first member and having a groove registering with said first groove, a lifting device adapted to be positioned in said grooves, means to secure said members together, and means to prevent the longitudinal movement of said lifting device through said grooves.

5. A container, comprising a hollow member having a portion of its walls reduced transversely, a groove in the surface of said reduced portion, a lifting device positioned within said groove, a member adapted to be positioned against said reduced portion and provided with a groove registering with said first groove and receiving a portion of said lifting device, and means to secure said members together.

6. A container, comprising a hollow member having a portion of its walls reduced transversely, a groove in the surface of said reduced portion, a lifting device positioned within said groove, a member adapted to be positioned against said reduced portion and provided with a groove registering with said first groove and receiving a portion of said lifting device, means to secure said members together, and a lateral projection on said lifting device extending beneath a portion of said second member to prevent a longitudinal displacement of said device from said members.

7. A container, comprising a hollow member having a portion of its walls reduced transversely, a groove in the surface of said reduced portion, a lifting device positioned within said groove, a member adapted to be positioned against said reduced portion and provided with a groove registering with said first groove and receiving a portion of said lifting device, means to secure said members together, and a lateral projection on said lifting device extending beneath a portion of said second member to prevent a longitudinal displacement of said device from said members, and said second member being provided with an inwardly directed flange adapted to secure an article within said first member.

WILLIAM KNOBLOCK.
